CONTOUR CHAIR

Ferdinand J. Katulski, East Detroit, Mich.

Application March 18, 1953, Serial No. 24,088

Term of patent 14 years

(Cl. D15—8)

To all whom it may concern:

Be it known that I, Ferdinand J. Katulski, a citizen of the United States residing in the city of East Detroit, State of Michigan, have invented a new, original, and ornamental Design for Contour Chair, of which the following is a specification, reference being had to the accompanying drawing, forming a part hereof.

Fig. 1 is a side perspective of a contour chair, showing my new design.

Fig. 2 is a front perspective view of the chair shown in Fig. 1; and

Fig. 3 is a section taken on line 3—3 of Fig. 2 to indicate the outline of the upholstery.

The characteristic features of the design reside in the solid line portion.

I claim:

The ornamental design for a contour chair, as shown and described.

FERDINAND J. KATULSKI.
